SEPARABLE ATTACHMENT-PLUG.

1 064,833

Specification of Letters Patent. Patented June 17, 1913.

Application filed January 2, 1912. Serial No. 669,253.

To all whom it may concern:

Be it known that I, HARVEY HUBBELL, a citizen of the United States, residing at Bridgeport, county of Fairfield, State of Connecticut, have invented an Improvement in Separable Attachment-Plugs, of which the following is a specification.

This invention has for its objects to simplify and to generally improve the construction and operation of separable attachment plugs.

With these and other objects in view the invention consists in certain novel constructions and combinations of parts which I will now describe, and then specifically point out in the claims hereunto appended.

In the accompanying drawing forming a part of this specification, Figure 1 is a longitudinal section on an enlarged scale, of the base of my novel attachment plug detached; Fig. 2 an elevation of one of the spring contacts detached, the one toward the right as seen in Fig. 1; Fig. 3 a section of the cap detached on the line 3—3 in Fig. 5, looking in the direction of the arrows, the binding screw being partly turned out; Fig. 4 a section of the cap on the line 4—4 in Fig. 5, looking in the direction of the arrows; Fig. 5 a plan view of the cap detached; Fig. 6 a section of a variant form of cap which is provided with a cord grip, the section line being indicated by 6—6 in Fig. 7; and Fig. 7 is a plan view corresponding with Fig. 6.

10 denotes the base and 11 the cap, both of which are made of insulating material, and 12 denotes the screw shell. The base has an external thread molded thereon which is engaged by the screw shell in the usual manner.

13 and 14 denote the base contacts which lie in recesses in the base, and 15 the contact blades which project from the cap. The contact blades are shown as rounded at their ends for convenience in engagement with the base contacts and as provided on opposite sides with recesses 16. The base contacts each comprise spring plates, indicated by 17, one or both being provided with inwardly extending lugs or indentations 18 at their edges (preferably formed by striking in the metal at the edges of the plates)

adapted to drop into and engage the recesses in the contact blades when the base and cap are connected, thus insuring an effective electrical connection between the contact blades and the base contacts and also an effective locking together of the two members. In making a connection, the rounded ends of the contact blades pass between the spring plates, the ends thereof engaging the lugs 18 and springing the plates outward until the recesses 16 are in coincidence with the lugs when the lugs will drop into the recesses and will retain the contact blades and spring plates in engagement. 65

The spring plates of base contact 13 are secured to a bracket 19 which is held in place by a center screw 20 and serves as a center contact for a socket (not shown). The spring plates of base contact 14 are secured 70 to a bracket 21 which rests upon a ledge on the base and is engaged and held in place by the overlying flange 22 of the screw shell. The parts in the base are thus reduced to the lowest possible number and the assembling is made perfectly simple. The contact blades are provided with base plates 23 which are engaged by the binding screws 24. A novel feature of the present cap is that the contact blades are secured in place in 80 the process of manufacture by the molding of the base plates into the material of the cap, the binding screws being left exposed in recesses 25.

31 denotes wires, 32 cords and 33 a cable. 85 In the form of cap illustrated in Figs. 3, 4 and 5, the end of the cable is received in a central recess 26 and the cords inclosing the wires are passed through holes 27 which intersect with or lead into binding screw recesses 25. The ends of the cords are stripped off leaving the wires exposed. The binding screw recesses just receive the binding screws freely and are ordinarily beveled outward slightly, as shown, for convenience in wiring. The wires are drawn through holes 27, passed around the binding screws in the usual manner and the screws are then tightened up. The advantage of this special construction is that 100 the wires cannot escape from under the binding screws and cannot be pushed upward.

through the cap but are always retained well down in the recesses by the binding screws, from which they cannot become detached.

In the form illustrated in Fig. 6, in addition to molding the base plates of the contact blades into the cap, I provide the cap with a simple and inexpensive cord grip. The cords inclosing the wires pass to the binding screws through holes 27 the same as before. At the base of recess 26 I provide a cone 28. The recess is threaded and is engaged by a screw plug 29 having a central hole 30 to receive the cable. The cords from the cable pass on opposite sides of the cone 15 through the holes 27 and are gripped between the cone and the end of the screw plug, the inner end of hole 30 being preferably chamfered off, as shown, to provide a gripping surface parallel with the cone. In assembling 20 this form, the cable is passed into hole 30, the cords are passed through holes 27 and the wires engaged with the binding screws, then the cords are slackened slightly and the screw plug is turned down to place, clamping 25 the cords, as already described, so that any pull upon the cable is taken up by the grip of the screw plug and cone upon the cords and no strain whatever can be placed upon the connection of the wires to the binding 30 screws.

Having thus described my invention I claim:

1. A separable attachment plug comprising a base, a cap, flat contact blades carried by said cap and having their opposite edges cut away to form recesses, and flat contact blades carried by said base the opposite edges of the last mentioned blades being provided with lugs or indentations adapted 35 to enter the recesses of the first mentioned blades when the cap and base are united.

2. A separable attachment plug comprising a base, a cap, flat contact blades carried by said cap and having their opposite edges 45 cut away to form recesses, and flat contact blades carried by said base and arranged in pairs, the opposite edges of one of the plates of each pair being provided with lugs or indentations adapted to enter the recesses of 50 the first mentioned blades when the cap and base are united.

3. An attachment plug cap formed of insulating material and provided with spaced apart recesses, contact blades provided with 55 base plates embedded within said insulating material, and each having a portion projecting into one of said recesses, and binding screws located in said recesses and engaging the projecting portion of the respective base plates.

4. An attachment plug cap formed of insulating material provided with a central bore and spaced apart recesses, said cap being provided with holes extending from

said bore to said recesses, contact blades provided with base plates embedded within said insulating material and each having a portion projecting into one of said recesses, and binding screws located in said recesses and engaging the projecting portions of the respective base plates. 65

5. An attachment plug base provided with recesses, brackets carrying contacts which extend into said recesses, a center screw engaging one bracket to retain the latter in 70 position, a screw shell having an overlying flange engaging the other bracket to retain the same in place, and means independent of said center screw for retaining said shell in position. 75

6. An attachment plug base provided with an annular ledge and longitudinal recesses, brackets carrying contacts which extend into said recesses, one of said brackets having a shoulder resting upon said ledge, a screw shell having a threaded engagement with 80 said base and provided with a flange engaging said shoulder to hold the second bracket in place, and a center screw for securing the other bracket in place. 85

7. An attachment plug base provided with an annular ledge and longitudinal recesses, brackets carrying contacts which extend into said recesses, said brackets being provided with angular supporting portions, 90 the supporting portion of one bracket resting upon said ledge, a screw shell having a threaded engagement with said base and provided with a flange overlying said ledge and engaging the supporting portion of the 95 last mentioned bracket, and a center screw engaging the angular portion of the other supporting bracket. 100

8. In a separable attachment plug, the combination with a base having a ledge and longitudinal recesses, contacts lying wholly within said recesses and insulated by the material of the base and brackets by which said contacts are carried, one of said brackets serving as a center contact, of a screw 105 engaging said bracket to hold the contact in place and a screw shell having an overlying flange between which and the ledge the other bracket is gripped. 110

9. An attachment plug base provided with an annular ledge and longitudinal recesses, brackets carrying contacts which extend into said recesses, one of said brackets having a shoulder resting upon said ledge, a screw shell surrounding said base and having a threaded engagement therewith, said screw shell being provided with a flange 115 engaging said shoulder to hold the second bracket in place, and a center screw for securing the other bracket in place. 120

10. An attachment plug base provided with an annular ledge and longitudinal recesses, brackets carrying contacts which ex- 125

tend into said recesses, said brackets being provided with angular supporting portions, the supporting portion of one bracket resting upon said ledge, a screw shell surrounding said base and having a threaded engagement therewith, said screw shell being provided with a flange engaging said shoulder to hold the second bracket in place, and a center screw engaging the angular portion of the other supporting bracket. 10

In testimony whereof I affix my signature in presence of two witnesses.

HARVEY HUBBELL.
